CLAIM

The ornamental design for a puzzle, as shown and described.

DESCRIPTION

FIG. 1 is an upper right perspective view of the puzzle in a first configuration, according to the new design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left elevation view thereof.

FIG. 7 is a right elevation view thereof.

FIG. 8 is an upper left perspective view of the puzzle in a second configuration, according to the new design.

FIG. 9 is a front elevation view thereof.

FIG. 10 is a rear elevation view thereof.

FIG. 11 is a top plan view thereof.

FIG. 12 is a bottom plan view thereof.

FIG. 13 is a left elevation view thereof.

FIG. 14 is a right elevation view thereof.

FIG. 15 is an upper right perspective view of the puzzle in a third configuration, according to the new design.

FIG. 16 is a front elevation view thereof.

FIG. 17 is a rear elevation view thereof.

FIG. 18 is a top plan view thereof.

FIG. 19 is a bottom plan view thereof.

FIG. 20 is a left elevation view thereof; and,

FIG. 21 is a right elevation view thereof.

1 Claim, 12 Drawing Sheets
